UNITED STATES PATENT OFFICE.

GEORGE DORELL COOPER, OF ST. JOHNS, MICHIGAN, ASSIGNOR TO
JESSIE COOPER, OF ST. JOHNS, MICHIGAN.

STEAM-GENERATOR.

SPECIFICATION forming part of Letters Patent No. 783,617, dated February 28, 1905.

Application filed October 27, 1904. Serial No. 230,190.

To all whom it may concern:

Be it known that I, GEORGE DORELL COOPER, a citizen of the United States of America, residing at St. Johns, in the county of Clinton 5 and State of Michigan, have invented certain new and useful Improvements in Steam-Generators, of which the following is a specification, reference being had therein to the accompanying drawings.

10 This invention relates to new and useful improvements in steam-generators, and has particular reference to that class of generators used for heating houses.

To this end the invention consists in the 15 novel construction of the generator involving the use of the fewest possible parts and of the water-jacketed fire-pot whereby the vertical water-wall may be directly supported upon the fire-pot in constant communication there- 20 with to maintain a circulation of the water therein; and the invention consists, further, in the peculiar construction, arrangement, and combination of parts, all as more fully hereinafter described, and shown in the accompa- 25 nying drawings, in which—

Figure 1 is a vertical transverse section through my improved generator and fire-pot; Fig. 2, a vertical central longitudinal section through the generator and fire-pot; Fig. 3, a 30 plan view of the fire-pot detached.

A is the fire-pot, provided with the annular water-space B and peripheral flange C, under the forward edge of which the transverse metal plate D projects, which entirely fills the 35 space between the boiler-front and fire-pot, said plate being let into the brick side walls at its opposite ends to form a support for the fire-pot at its forward end.

E represents laterally-extending lugs integrally formed with the fire-pot near its rear end and adapted to be let into the brick side walls to support the fire-pot therefrom in conjunction with the plate D, which plate may, if desired, be made integral with the fire-pot. 45

G is a vertical water-wall adapted to be secured to the top of the fire-pot at its rear edge by screw-bolts H, passing through apertured ears I on the water-wall and fire-pot, respectively, the meeting faces of the fire-pot and

water-wall being faced off to form a tight 50 joint, communicating with each other through openings in the fire-pot and water-wall, respectively.

J represents stay-bolts connecting the front and rear water-walls. 55

K represents the water-tubes projecting from the front side of the water-wall, closed at their outer ends and threaded into openings in the water-wall at their inner ends, said tubes being preferably inclined slightly upwardly to cause the water to drain toward the water-wall. 60

L is the steam-drum, supported upon the vertical water-wall by screw-bolts M, passing through apertured ears N on the drum and 65 wall, respectively, said drum communicating with the water-wall through the passage O.

P is the smoke-stack, R the boiler-front provided with the usual fire and ash-pit doors S T, and U is the grate supported within the 70 fire-pot, so that the heat of the fire will heat the walls of the fire-pot and water contained therein, thereby causing an upward circulation of the same, thus utilizing what would be waste heat to initially heat the water, which I find to be 75 a great advantage and saving in this type of heaters.

By arranging the water-tubes in the form of an arch a fire-chamber is formed giving ready access to the fire-pot which holds the 80 fire, and by providing the fire-pot with a water-jacket forming part of the circulating system it acts both to prevent the fire-pot from burning out and utilizing the waste heat to heat the water therein, thus greatly increasing 85 the circulation.

The water-wall and fire-pot being each integrally cast in one piece with the lateral lugs and the steam-drum in another piece, it forms a simple and cheap construction with but two 90 joints, which can be easily connected together by screw-bolts, thus making a heater which any ordinary steam-fitter can set up without the use of special tools.

Having thus fully described my invention, 95 what I claim is—

1. In a steam-generator, the combination of a fire-pot formed with an annular water-space

- and laterally-extending supporting-lugs, a water-wall supported on the rear end of the fire-pot, a steam-drum supported at one end by said wall and water-tubes closed at one end and 5 communicating with the water-space of the wall at their opposite ends, said tubes being arranged to form an arch over the fire-pot.
2. In a steam-generator, the combination of a fire-pot formed with an annular water-space, 10 a water-wall formed with apertured lugs at its opposite ends, apertured lugs on the fire-pot registering with the lugs on the lower end of the wall and bolts connecting said lugs, a steam-drum supported by said wall, bolts passing 15 through lugs on the adjacent ends of said drum and wall rigidly uniting said drum and wall, and water-tubes closed at one end and communicating with the water-space of the wall at their opposite ends.
- 20 3. In a steam-generator, the combination of a fire-pot integrally formed with an annular water-space and laterally-extending lugs forming the supporting means for the fire-pot, a vertical water-wall supported on the fire-pot, 25 lugs formed with apertures on the lower end of the water-wall, bolts connecting said water-wall and fire-pot through said apertured lugs, a steam-drum wholly supported by said wall, apertured lugs on the drum and wall, bolts 30 uniting said drum and wall through said apertured lugs, and water-tubes closed at one end and communicating with the water-space of the wall at their opposite ends, said tubes being arranged to form an arch over the fire-pot.
- 35 4. In a steam-generator, the combination with the casing, of a fire-pot formed with an annular water-space and a peripheral flange around its upper edge, oppositely-disposed lugs on the fire-pot adapted to be let into the 40 walls of the casing, a horizontal plate adapted to engage the peripheral flange to fill the space between the fire-pot and wall and forming in conjunction with said lugs the means for supporting the fire-pot, a vertical water- 45 wall supported on the fire-pot and communicating therewith, a steam-drum at the upper end of said wall and communicating therewith, and water-tubes closed at their outer ends and communicating with the water-wall at their 50 inner ends.
5. In a steam-generator, the combination with the casing, of a fire-pot integrally formed with an annular water-space and a peripheral flange, oppositely-disposed lugs integrally 55 formed with said flange and adapted to support the fire-pot, a plate engaging said flange and adapted to separate the fire-chamber from the ash-pit, a vertical water-wall communicating with the water-space of the fire-pot and 60 supported thereon, means for securing the water-wall and fire-pot together, a cylindrical

steam-drum supported by said wall and water-tubes communicating at their inner ends with the water-space of the wall, said tubes being closed at their outer ends.

65

6. In a steam-generator, the combination with the walls or casing, of a fire-pot formed with an annular water-space and a peripheral flange around its upper edge, oppositely-disposed lugs forming a continuation of said flange adapted to be let into the side walls to support the rear end of the fire-pot, a plate engaging said flange adapted to be let into the side walls to support the front end of the fire-pot and separate the fire-chamber from the 70 ash-pit, a vertical water-wall supported on the fire-pot and communicating therewith, a horizontal cylindrical steam-drum communicating with and supported by said wall at its upper end and water-tubes closed at their outer ends 75 communicating with the water-space of the wall at their inner ends.

80

7. In a steam-generator, the combination with the steam-drum, of the vertical water-wall supporting said drum, a plurality of water-tubes communicating with the water-wall, said wall having openings in its lower portion and integrally formed with oppositely-disposed apertured ears, a fire-pot formed with a peripheral flange and an annular water-space 90 having openings adapted to register with the openings in the water-wall, bolts passing through said ears and forming the means for uniting the water-wall and fire-pot, lugs on one end of the fire-pot and a plate adapted to 95 engage the peripheral flange at the opposite end of the fire-pot to form the supporting means therefor.

85

8. In a steam-generator, the combination with the horizontal cylindrical steam-drum, of the vertical water-wall supporting said drum at one end and communicating therewith, said wall having openings in its lower end and provided with oppositely-extending apertured ears, a plurality of water-tubes closed at their 100 outer ends and communicating with the water-wall at their inner ends said tubes arranged in the form of an arch to form a fire-chamber extending the full length of said tubes, a fire-pot formed with an annular water-space having 105 openings registering with the openings in the water-wall, bolts passing through said apertured ears for securing the water-wall and fire-pot together, and oppositely-disposed lugs on the fire-pot forming the supporting means 110 for the fire-pot.

110

In testimony whereof I affix my signature in presence of two witnesses.

GEORGE DORELL COOPER.
